UNITED STATES PATENT OFFICE.

CARL H. PRÜSMANN, OF BUCKAU-MAGDEBURG, GERMANY, ASSIGNOR TO
SCHAFFER & BUDENBERG, OF SAME PLACE.

TACHOMETER.

SPECIFICATION forming part of Letters Patent No. 288,593, dated November 13, 1883.

Application filed July 26, 1883. (No model.)

To all whom it may concern:

Be it known that I, CARL HEINRICH PRÜSMANN, a citizen of Germany, residing at Buckau-Magdeburg, Germany, have invented new and useful Improvements in Tachometers, of which the following is a specification.

This invention relates to improvements in tachometers, and has for its object to provide novel means for actuating the index-hand; to which end the invention consists in the construction and combination of devices herein-after described and claimed, and illustrated in the accompanying drawings, in which—

Figure 1 is a face view of the apparatus, partly in section. Fig. 2 is a side view partly in section.

Similar letters indicate corresponding parts.

The letter A indicates the casing of the apparatus, made of sheet metal or other suitable material. The front of the case is provided with a glass plate, to expose the index and prevent dust and strange matter from entering.

The operation of the apparatus, as is the case in most of these instruments, is based upon the effect of centrifugal force. In the case A turns the shaft w, with the oscillating ring O. This ring O is adapted to oscillate about pivots c c, extending from the shaft w, and a spring or springs, F, have a tendency to throw said ring into a position coincident to that of the longitudinal axis of the shaft w and cause said ring to assume the position shown in Fig. 1, when the parts are at rest.

To the oscillating ring O are connected, by means of a pivot or pintle, b, arms S S, which arms, at their other ends, are connected by pivots or pintles d to a sliding piece, K. This sliding piece K sits over the end of the shaft w and moves readily thereon in a longitudinal direction.

R indicates a pulley, which serves to connect the instrument with any suitable part of a machine by a belt. If, now, the pulley R, and with it the shaft w, are caused to revolve, the centrifugal force tends to cause the ring O to turn about the pivots c against the resistance of the springs F. This motion of the ring O, being communicated to the arms S S, forces the sliding piece K outward or away from the shaft w. The sliding piece K, pressing upon the lever x, communicates motion to the seg-

ment u and to the hand Z in any well-known manner. A spiral spring, f, which lies about the axis of the hand Z, causes the hand Z to return to the starting-point, and presses the end of the lever x continually against the point of the sliding piece K. The faster the velocity of the machine the faster will the axis w revolve, and the resulting increased centrifugal force, acting on the ring O, will cause the sliding piece K to be further pushed out, and will cause the hand Z to pass over the dial in the direction of the arrow, thereby furnishing a means for determining the velocity of the revolution of the pulley R. Numbers 65 on the dial-plate are empirically arranged to indicate the velocity of revolution of the pulley R, thus enabling the velocity to be read from the indication of the hand Z on the dial.

The apparatus constructed as above described provides efficient means for continuously indicating the number of revolutions of a shaft within a given period of time, and at the same time the structure is simple, and not liable to become disarranged.

I am aware that it is not broadly new to arrange a governor or oscillating arm or disk on a revolving shaft to actuate an index-hand by the centrifugal force or action of such governor or oscillating arm or disk, and such, therefore, I do not claim; but

What I claim as new, and desire to secure by Letters Patent, is—

1. The combination of the casing A, having a glass front, a shaft, w, held against longitudinal movement, but free to revolve in a bearing on the case, and carrying a pulley at its outer end, a longitudinally-sliding piece, K, arranged upon the inner end of the shaft, and having its end arranged to press a lever, x, to communicate motion to the index-hand Z, the ring O, oscillating on pivots projecting laterally from the shaft within the casing, and arms S, pivoted at one end to the sliding piece on the shaft and at the other end directly to the oscillating ring, substantially as described.

2. The combination of the casing A, having a glass front, a shaft, w, held against longitudinal movement, but free to revolve in a bearing on the casing, and having a pulley at its outer end, a longitudinally-sliding piece, K, arranged

upon the inner end of the shaft, and having its end arranged to press a lever, *x*, for moving the index-hand *Z*, the ring *O*, mounted upon pivots projecting laterally from the shaft with-
5 in the case, springs *F*, coiled upon the pivots of the ring, and arms *S*, pivoted at one end to the sliding piece and at the other end to the ring, said members being arranged to operate substantially as described.

In testimony whereof I have hereunto set my hand in the presence of two subscribing witnesses.

CARL HEINRICH PRÜSMANN.
